United States Patent Office

Des. 218,789
Patented Sept. 22, 1970

218,789

DISPLAY TRAY FOR SHOW CASES OR THE LIKE

James C. Ferguson, Roselle Park, N.J., assignor to Fairmont Electronics Inc., Holyoke, Mass.

Filed Mar. 13, 1969, Ser. No. 16,234

Term of patent 14 years

Int. Cl. D6—01

U.S. Cl. D80—9

FIG. 1

FIG. 2

FIG. 1 is a perspective view taken from the top, front and one side of a display tray for show cases and the like, showing my new design; and

FIG. 2 is a front elevational view thereof.

I claim:

The ornamental design for a display tray for show cases or the like, as shown.
